UNITED STATES PATENT OFFICE.

JOHN KIRKALDY, OF 40 WEST INDIA DOCK ROAD, COUNTY OF MIDDLESEX, ENGLAND.

FEED-WATER HEATER.

SPECIFICATION forming part of Letters Patent No. 398,283, dated February 19, 1889.

Application filed August 27, 1888. Serial No. 283,829. (No model.) Patented in England April 3, 1886, No. 4,707; in France December 4, 1886, No. 180,073; in Belgium December 6, 1886, No. 75,497; in Italy December 31, 1886, No. 20,949; in Victoria January 12, 1887, No. 4,891; in South Australia January 24, 1887, No. 763; in Queensland February 2, 1887, No. 246; in New South Wales March 31, 1887, No. 2,047, and in Canada March 6, 1888, No. 28,633.

To all whom it may concern:

Be it known that I, JOHN KIRKALDY, engineer, a subject of the Queen of Great Britain, residing at 40 West India Dock Road, in the county of Middlesex, England, have invented certain new and useful improvements in apparatus used for enabling loss of water from the steam-boilers of steam-engines to be replaced, and for heating the feed-water and maintaining a vacuum, (for which I have obtained Letters Patent in Great Britain, No. 4,707, dated April 3, 1886; in France, No. 180,073, dated December 4, 1886; in Belgium, No. 75,497, dated December 6, 1886; in Italy, No. 20,949, dated December 31, 1886; in Canada, No. 28,633, dated March 6, 1888; in New South Wales, No. 2,047, dated March 31, 1887; in Victoria, No. 4,891, dated January 12, 1887; in South Australia, No. 763, dated January 24, 1887, and in Queensland, No. 246, dated February 2, 1887,) of which the following is a specification.

Although the exhaust-steam from engines fitted with surface condensers is passed back to the boilers as water, there is a small waste of water in the cycle—from boiler to engine and engine to boiler—which must be made up by water occasionally added to the boiler from without. To effect this, I vaporize a portion of the circulating water (which has become heated by abstracting heat from the steam passing into the condenser) by bringing such already-heated water into contact with surfaces heated by the exhaust-steam on its way from the engine to the condenser, and I connect the chamber into which the vapor rises by a pipe with the condenser of the engine, so that it is condensed in this condenser together with the steam which passes from the engine. The water drawn off from the condenser I also cause to be passed through a feed-water heater, where it is heated nearly to the boiling-point by exhaust-steam before it enters the boilers. The feed-water heater, the evaporator, and the condenser I place one above the other or alongside of each other, as hereinafter described, so as to form them into one compact apparatus.

Figure 1 is an elevation, partly in section, of one form of apparatus constructed according to my invention, in which the feed-heater, evaporator, and condenser are placed one above the other. Fig. 2 is a side elevation, and Fig. 3 a plan of a modification, in which these three parts are in a row alongside of one another. Fig. 4 is a side elevation, and Fig. 5 a plan of a similar construction, with the three parts side by side and ranged in a triangle, and with a small steam-engine combined with them of sufficient power for working the air-pumps, circulating-pumps, and feed-pumps for the main engines. Fig. 6 is an elevation, partly in section, and Fig. 7 an end view, of a modification in which the evaporator is placed above the top of a marine boiler of ordinary type.

In Fig. 1 A is the feed-water heater, B the evaporator, and C the condenser. The heater is composed of a cylindrical casing with tube-plates *a a* across its ends and with coiled pipes *a'* passing through the casing from one tube-plate to the other. Above the upper tube-plate is a dome-cover, to which exhaust-steam from the engine is admitted by the inlet *D*. The feed-water to be heated is admitted by the pipe *E* to the cylindrical casing of the heater A and passes off to the boilers through the outlet *E'*, after being heated by the exhaust-steam passing through the coiled pipes *a'*. The evaporator is composed of a cylindrical casing with tube-plates *b b* passing across its ends, and with coiled pipes *b'* passing through the casing from one tube-plate to the other. The evaporator is separated from the heater by a steam-space, F, in the outer cylindrical casing of which are doors *F'*, to allow of the tube-connections being readily got at. The condenser C is formed similarly to the evaporator and heater, with tube *c'* and tube-plate *c*. At the top it is separated from the evaporator by a steam-space, G. Circulating or cooling water is admitted to the lower part of the cylindrical casing of the condenser C by the pipe *H*, and passes away from the upper part of this casing by the pipe *I*. The cylindrical casing of the evaporator is kept about

half full of water drawn from the upper part of the cylindrical casing of the condenser through the pipe J, fitted with a tap, J'. K is a gage-glass, by which the height of water in the evaporator can be seen. L is a pipe by which vapor produced in the cylindrical casing of the evaporator is led away to the steam-space G, so that it may pass to the condenser-tubes, together with the exhaust-steam from the engine. M is a well or chamber below the bottom of the condenser, in which water resulting from the condensation of the steam accumulates, and is drawn off by the feed-pumps of the engine, to be supplied to the heater A through the pipe E, and thence to the boilers through the pipe E'.

In Figs. 2 and 3 the feed-water heater A, evaporator B, and condenser C are placed in a line side by side. The bottom chamber of the feed-water heater is connected by a pipe, A', with the top chamber of the evaporator, and the bottom chamber of the evaporator is connected by a pipe, B', with the top chamber of the condenser. The exhaust-steam from an engine enters the top chamber of the feed-water heater through the pipe D, while a pipe, M', passes from the bottom chamber of the condenser to the air-pump of the engine. The feed-water to be heated passes into the bottom of the casing of the feed-heater through the pipe E, and passes off from the top to the boiler through the pipe E'. Cooling or circulating water is supplied to the bottom of the condenser through the pipe H, and passes off at the top through the pipe I. Part of the circulating water, which has become heated in its passage through the condenser-casing, can from time to time be drawn off into the casing of the evaporator through the pipe J. L is a pipe leading from the upper part of the evaporator-casing, by which vapor produced in the evaporator is conveyed to the condenser to be condensed with the exhaust-steam from the engine. K is a gage-glass for indicating the height of water in the evaporator.

In Figs. 4 and 5 A is the feed-water heater, B the evaporator, and C the condenser. O O are the steam-cylinders of the auxiliary engine. P P are the air-pumps, and Q Q the pumps for delivering circulating or cooling water to the condenser. H' is the suction-pipe for the circulating-pumps H, the delivery-pipe passing from the pumps to the bottom of the condenser-casing. I is the circulating delivery-pipe from the top of the condenser-casing. D is the exhaust from the main engine to the feed-heater; D', exhaust from auxiliary engine to the feed-heater. A' is the exhaust from the bottom of the feed-heater to the top of the evaporator, and B' the exhaust from the bottom of the evaporator to the top of the condenser. M' is the air-pump suction passing from the bottom chamber of the condenser, and M² the air-pump delivery. R is the steam-supply pipe to the cylinders of the auxiliary. J is the pipe by which a portion of the heated

circulating water can be led off from the top of the condenser-casing to the evaporator. L is a pipe to convey vapor from the upper part of the evaporator to the condenser, and E' is the pipe by which heated feed-water passes off to the boilers.

In the construction shown at Figs. 6 and 7 the condenser C is of the ordinary type used with marine engines. B is an evaporator placed above it. J is a pipe fitted with a tap, J', by which part of the circulating or cooling water can be drawn from the condenser into the evaporator. L is a pipe by which vapor produced in the evaporator is led away to the interior of the condenser. D is the inlet by which exhaust-steam from the engine is admitted to the steam-tubes of the evaporator. From the lower ends of the tubes the steam passes into the interior of the ordinary condenser. M is a pipe fitted with a cock, by which brine residuum can be drawn off from time to time by a brine-pump. N is a pipe fitted with a cock, by which impurities floating on the surface of the water may from time to time be drawn off.

Having now particularly described and ascertained the nature of my said invention and in what manner the same is to be performed, I declare that what I claim is—

1. The combination, substantially as hereinbefore set forth, of the feed-water heater, the condenser, the evaporator interposed between the feed-water heater and the condenser, and exhaust-steam pipes passing through the heater, the evaporator, and the condenser, the inlet and outlet openings for feed-water in the feed-water heater, the inlet and outlet openings for cooling-water in the condenser, and the pipes connecting the condenser with the evaporator.

2. The combination, substantially as hereinbefore set forth, of the condenser, the evaporator arranged above the condenser and communicating therewith, the feed-water heater arranged above the evaporator, the exhaust-steam pipes extending through the heater, the evaporator, and the condenser, the inlet and outlet openings in the condenser for cooling-water, the inlet and outlet openings in the heater for feed-water, a pipe leading from the condenser to the evaporator conveying warmed water from the condenser to the evaporator, and the vapor-pipe leading from the top of the evaporator to the condenser.

3. The combination, substantially as hereinbefore set forth, of the condenser, the evaporator arranged above the condenser, the coiled exhaust-steam pipes in the evaporator, the vapor-pipe leading from the upper part of the evaporator to the condenser, and a pipe connecting the evaporator with the condenser, whereby water warmed in the condenser is carried to the evaporator.

4. The combination of a feed-water heater, an evaporator, and a surface condenser having pipes passing through each, through which exhaust-steam is passed successively, a feed-

pipe leading from the condenser to the evaporator for supplying water which has become heated in the condenser from the condenser-casing to the casing of the evaporator, and a vapor-pipe passing from the upper part of the evaporator-casing to the interior of the condenser, substantially as set forth.

5. The combination of an evaporator and a surface condenser having pipes passing through each, through which exhaust-steam is passed successively, a feed-pipe for supply-

ing water which has become heated in the condenser from the condenser-casing to the casing of the evaporator, and a vapor-pipe passing from the upper part of the evaporator to the interior of the condenser, substantially as set forth. 15

JOHN KIRKALDY.
